(57) **CLAIM**

The ornamental design for the bed frame, as shown and described.

DESCRIPTION

FIG. 1 is a front elevational view of a bed frame incorporating the design of my new invention;

FIG. 2 is a rear elevational view thereof;

FIG. 3 is a right side elevational view thereof, with the left side elevational view being a mirror image thereof;

FIG. 4 is a top plan view thereof;

FIG. 5 is a bottom plan view thereof;

FIG. 6 is a vertical cross-sectional view along line 6—6 of FIG. 3, depicting the front surface of the headboard; and,

FIG. 7 is a vertical cross-sectional view along line 7—7 of FIG. 3, depicting the rear surface of the footboard.
